UNITED STATES PATENT OFFICE.

CHARLES E. POPE, DECEASED, LATE OF SPRINGFIELD, MASSACHUSETTS, BY MARY A. POPE, EXECUTRIX, OF SPRINGFIELD, MASSACHUSETTS, ASSIGNOR TO GREAT NORTHERN PAPER COMPANY, OF MILLINOCKET, MAINE, A CORPORATION OF MAINE.

PAPER-MAKING MACHINE.

Application filed April 21, 1923. Serial No. 633,809.

This invention relates to paper-making machines wherein the paper pulp is deposited, or the paper is made, on a rotating perforated cylinder and transferred to a traveling felt; and the invention has for its object to improve the construction and operation of cylinder paper-making machines.

Fig. 1 is a plan view of a cylinder paper-making machine embodying the invention.

10 Fig. 2 is a sectional elevation of the machine of Fig. 1.

Fig. 3 is a sectional detail through the cylinder and a suction box disposed therein at and above the level of the water in the pulp-containing tank.

15 Fig. 4 is a detail of the cylinder in side elevation and partly in section.

As here shown, the cylinder paper-making machine may include the pulp-containing tank 10 which may be formed with a compartment having the more or less semi-circularly formed bottom wall 11; and a paper-making cylinder 12 is adapted to rotate in said compartment in spaced relation

20 with the bottom wall thereof. One end of said tank may be formed with a plurality of vertically-disposed passages 13 arranged in communication at the upper and lower ends thereof and through which the pulp

25 is adapted to flow from the pipe 14 into the cylinder-compartment. The bottom wall 11 of said cylinder-compartment may extend upwardly on the pulp-entrance side of the tank to provide a ledge or dam 15 over

30 which the pulp-bearing water is adapted to flow to enter said cylinder-compartment. The other end of said bottom wall 11 may also form a dam 16 over which surplus pulp

35 may flow and pass into a compartment 17 of said tank, from which it is conducted away.

The paper-making cylinder 12 may be formed or provided with the cylindrical shell 18 having the perforations or openings

45 19 through which water is adapted to flow freely. A paper-making wire 20 is adapted to cover the periphery of said shell over the perforations 18 thereof; and the paper-pulp is adapted to be laid or deposited on said

50 wire as the pulp-containing water flows through the wire into the interior of the cylinder. The ends of said shell may be

secured to end-plates 22, one of which may be provided with gear teeth 23 at its periphery which are adapted to mesh with a 55 pinion gear 24 carried by a drive shaft 25, whereby said cylinder may be rotated at a suitable speed. Said end plates 22 are or may be formed with openings 26 there-through which communicate with the interior of the cylinder, and water which passes into the interior of the cylinder through the paper-making wire is or may be drained from the cylinder through said openings 26 and pass beyond the cylinder 60 and tank through openings in the side walls of the tank, by gravity or suction. Said end-plates 22 are also formed or provided with hubs 27 having passages 28 there-through in which a stationarily-supported 70 hollow shaft 30 is extended and on which said cylinder is rotatably-supported. The particular means of supporting and driving the cylinder is not important, so far as this invention is concerned, and other suitable 75 means may be provided.

Said cylinder is adapted to rotate partially immersed in the pulp in said cylinder-compartment. The water in the pulp is adapted to flow through the perforations 80 in the cylinder and the pulp is continuously deposited in a layer on the periphery thereof as the cylinder is rotated. The pulp layer on the cylinder is moved above the water level in the cylinder compartment, 85 which level may be substantially at or slightly above the top of the dam 16, and is taken off by means including a traveling felt, hereinafter to be described.

When the wet pulp layer on the cylinder 90 is moved above the surface of the water by the rotation of the cylinder, it is no longer pressed positively against the cylinder by the pressure of water against it but, on the contrary, it is subject to centrifugal 95 force, due to the rotation of the cylinder and to other disintegrating forces so that particles from the pulp layer may be thrown off the surface of the cylinder; and the resulting paper sheet may be formed with a 100 plurality of small openings and may be of uneven thickness and, therefore, highly unsatisfactory. To avoid this, it is usual to run the cylinder at such a slow peripheral

speed that the paper output is low, compared to Fourdrinier machine making newspaper.

By applying suction through the shell of the cylinder to the paper at, and not below 5 and for a suitable distance above the water level, by the method herein described pulp particles are largely prevented from being thrown off the paper sheet, and the sheet is much improved and, furthermore, the peripheral speed of the cylinder, and, consequently, the output of the machine may be substantially increased.

For this purpose, the shell 18 of the cylinder is formed with a smooth cylindrical inner periphery and a suction box 35 is adapted to be stationarily-supported adjacent the inner periphery of said shell and act on the paper-layer on the outer periphery thereof through the perforations in 15 the shell. Said suction box is or may be supported, at each end, by means including the horizontal pipes 36 which are threaded into said box and are also threaded into members 37, which latter are fixedly clamped 20 or otherwise secured to said hollow shaft 30 and register with lateral openings therein whereby to establish communication between said shaft and the interior of the suction box. Said hollow shaft 30 is adapted to be 25 placed in communication with a suitable source of suction, not shown.

Said suction box 35 may be adjusted toward or away from the inner periphery of the shell of said cylinder in any suitable 35 manner, as, for instance, by rotating said pipes 36 in the proper direction, and the screw-threads at the ends thereof may be respectively right and left hand, for this purpose.

40 Said suction box 35, in accordance with this invention, is adapted to be placed so that the bottom edge of the opening therein is approximately at the water line in the cylinder-compartment of the tank and so 45 nearly all of the opening extends upwardly above the water line, whereby to exert a suction effect on the paper sheet immediately at and above the surface of the water, without at the same time pumping too much 50 water. With this arrangement, as above stated, a better grade of paper is produced and the output of the machine may be increased as the suction effect holds the pulp particles to the cylinder until they are sufficiently dry to adhere thereto without 55 assistance.

Suction devices have previously been used 60 in connection with pulp forming cylinders running at low speed, and I do not claim broadly the use of a suction device within a forming cylinder; but so far as I am aware the previous devices have not been designed to accomplish the work of holding the newly 65 formed sheet against the cylinder as it emerges from the water, and thus maintain-

ing the formed sheet on the wire against a high centrifugal force and the other peeling-off forces.

The paper sheet is or may be removed 70 from the paper-making cylinder by any suitable means as, for instance, a traveling felt 40, which is passed over a tension roll 41 and a couch roll 40 disposed at the upper part of the cylinder and adapted to hold the 75 felt in contact with the paper sheet on the cylinder and pick up the paper sheet and transfer it, as formed, to other components of a paper-making machine, as the press rolls, and the driers. Said felt is made to travel in the direction of and substantially 80 at the linear speed of the paper sheet on the cylinder.

The extent of suction to be used in the suction box above described must not be so great as to prevent the sheet from being 85 removed by the couch, nor, on the other hand, so little as to permit the newly formed sheet to leave the cylinder. The extent of this suction may be varied within wide 90 limits, and can be readily determined by experiment, it being obvious the suction should be increased according to the speed of the machine.

What is claimed is—

A paper making machine having the combination of a pulp-containing tank having a cylinder compartment, a paper making cylinder rotatable in said compartment having a horizontal perforate cylindrical wall on which the paper sheet is made and being open at the ends of the cylinder substantially to the inner face of said cylindrical wall so that the water passing into the interior of the cylinder can pass freely horizontally 95 out through said open ends without forming a pool within the cylinder, a stationarily-supported hollow shaft constituting a support on which said cylinder is rotatable, said cylinder compartment having a pulp inlet and a dam opposite said inlet over the horizontal top edge of which surplus pulp is 100 adapted to flow out of said compartment, said horizontal top edge being terminated slightly below the horizontal axis of said horizontal shaft, a suction box located within 105 said cylinder against the inner face of said cylindrical wall, having its lower horizontal edge located in horizontal alignment with the top of said dam and its upper edge located a substantial distance above the top 110 of said dam, whereby to apply suction to the paper sheet at and above but not below the point where the pulp sheet emerges from 115 from the liquid level in said cylinder compartment and to hold the paper sheet intact on the cylinder against the washing effect of the liquid in the tank thereon at such point, said suction box having an opening at its rear wall which is in horizontal 120 line with said hollow shaft, said shaft hav- 125 130

- ing an opening through its wall on the side of and in alignment with the opening in said suction box, a clamping member clamped about said shaft having an opening there-
5 in aligned and in communication with said shaft-opening, a horizontal suction pipe having right and left hand screw-threaded connections with said clamping member and said suction box in the openings thereof,
10 the arrangement of said suction box, suction pipe and shaft being such that water and air can pass from said suction box into said shaft at different levels without intermixing, and take-off mechanism for the paper sheet including a travelling felt, and means 15 to maintain said felt in contact with the paper sheet on the top of said cylinder.

In testimony whereof, I have signed my name to this specification.

MARY A. POPE,
Executrix of the will of Charles E. Pope.
